US00D921740S

(12) **United States Design Patent** (10) Patent No.: **US D921,740 S**
(45) Date of Patent: **** Jun. 8, 2021**

(54) **CAMERA**

(71) Applicant: **GoPro, Inc.**, San Mateo, CA (US)

(72) Inventors: **Daniel J. Coster**, San Francisco, CA (US); **Hernan Au**, San Mateo, CA (US); **Huy Phuong Nguyen**, San Mateo, CA (US); **Senka Agic Bergman**, Montara, CA (US)

(73) Assignee: **GoPro, Inc.**, San Mateo, CA (US)

(**) Term: **15 Years**

(21) Appl. No.: **29/765,003**

(22) Filed: **Jan. 5, 2021**

(57) **CLAIM**

The ornamental design for a camera, as shown and described.

DESCRIPTION

FIG. 1 is a top, front and right side perspective view of a camera showing our new design;

FIG. 2 is a bottom, rear and left side perspective view thereof;

FIG. 3 is a front elevation view thereof;

FIG. 4 is a rear elevation view thereof;

FIG. 5 is a right side elevation view thereof;

FIG. 6 is a left side elevation view thereof;

FIG. 7 is a top plan view thereof; and,

FIG. 8 is a bottom plan view thereof.

The broken lines depict portions of the camera in which the design is embodied that form no part of the claimed design.

1 Claim, 7 Drawing Sheets
